UNITED STATES PATENT OFFICE.

EMIL A. SCHUELKE, OF MERIDEN, CONNECTICUT, ASSIGNOR TO THE NAPIER CO., OF MERIDEN, CONNECTICUT, A CORPORATION.

DESIGN FOR A POCKET LIGHTER.

Application filed August 19, 1927. Serial No. 23,150. Term of patent 14 years.

To all whom it may concern:

Be it known that I, EMIL A. SCHUELKE, a citizen of the United States, residing at Meriden, in the county of New Haven and State of Connecticut, have invented a new, original, and ornamental Design for a Pocket Lighter, of which the following is a specification, reference being had to the accompanying drawing, forming part thereof.

Fig. 1 is a side view of a pocket lighter showing my new design; and

Fig. 2 is an edge view of the same.

Fig. 3 is a top view of the same.

I claim:

The ornamental design for a pocket lighter as shown.

EMIL A. SCHUELKE.
